PORTABLE COOKING STOVE OR SIMILAR ARTICLE

William Rakocy, Clifton, N.J., assignor to Ronson Corporation, Woodbridge, N.J., a corporation of New Jersey

Filed Sept. 11, 1967, Ser. No. 8,554

Term of patent 14 years

(Cl. D81—10)

FIG. 1 is a perspective view of a portable cooking stove showing my new design;

FIG. 2 is a top view thereof;

FIG. 3 is a bottom view thereof;

FIG. 4 is a side view thereof;

FIG. 5 is a front view thereof;

FIG. 6 is a rear view thereof;

I claim:

The ornamental design for a portable cooking stove or similar article, substantially as shown.
